UNITED STATES PATENT OFFICE.

EVERETT H. WHITE, OF ST. PAUL, MINNESOTA.

HEAT-REGULATOR.

1,271,815.

Specification of Letters Patent.

Patented July 9, 1918.

Application filed January 10, 1916. Serial No. 71,350.

To all whom it may concern:

Be it known that I, EVERETT H. WHITE, a citizen of the United States, residing at St. Paul, in the county of Ramsey and State of Minnesota, have invented certain new and useful Improvements in Heat-Regulators, of which the following is a specification.

My invention relates to heat regulators and has for its object to provide an improved device for making and breaking electric circuits governed by the temperature of the room in which the device is set, the making and breaking of said circuits operating damper controlling mechanism (not shown) by which the furnace is regulated. In carrying out my invention I employ an expansible chamber or set of chambers filled with ether gas as the thermostatic element, since I have discovered that the use of ether gas in such an expansible chamber gives a maximum of sensitiveness and force of movement of the circuit-controlling member. The contact - making member or pointer is pivotally mounted on the support for the thermostatic member, which in turn is pivotally mounted, so that the entire thermostatic member may be oscillated relatively to the contact members. In this manner the thermostatic member is adjusted so as to operate to close the circuits at any desired temperature.

It is a further object of my invention to provide the ether gas containers in the form of one or more hollow disk-shaped bodies which are held in planes parallel to the plane of movement of the contact arm. The expansion movement of these gas containers is applied to lever mechanism which translates the motion into a plane perpendicular to the line of movement of the point of application of force from the thermostats, this lever mechanism greatly simplifying such movement.

The full objects and advantages of my invention will appear in connection with the detailed description thereof and are particularly pointed out in the claims.

In the drawings, illustrating the application of my invention in one form,—

Figure 1 is a front elevational view of my improved thermostat with the cover removed and some of the parts shown in dotted lines. Fig. 2 is a longitudinal side sectional view of the same taken substantially through the center. Fig. 3 is a view similar to Fig. 2 showing a different form of case

with part of the same cut away. Fig. 4 is a plan view of the same device shown in Fig. 3 with a guard attached to the case. Fig. 5 is a front elevational view of a part 60 of the device shown in Fig. 4.

My invention comprises a metal back 10 having turned-up edges 11 and 12 to which are attached an ornamental casing or cover 13. The back 10 is of heavier metal than the cover and serves to support the operating parts. Pivotaly attached to the back 10 by a screw 14 is a casting 15 having a bearing shoulder 16 resting upon the surface of back 10. This shoulder allows the 70 casting 15 to oscillate without excess play and so holds the parts attached thereto in the proper relation to the other parts of the thermostat. Issuing from the central portion of casting 15 is a lug 17 which terminates in two bosses 18 and 19. Boss 18 is threaded to receive a stud 20 to which is attached the thermostatic device, as best seen in Fig. 2. The latter device comprises a pair of corrugated discoidal members 21 80 and 22 which are hollow and communicate with each other but are sealed from the atmosphere and which contain a gas readily acted upon by heat to cause said members to spread apart in the usual manner. At the 85 upper portion of casting 15 are a pair of parallel supports or lugs 24 and 25 extending out beyond the thermostatic member 22, between which are pivoted at 28 an L-shaped 90 lever having legs 26 and 27. Leg 26 is arranged to be engaged by a peg 23 secured to the member 22, and leg 27 is free to oscillate between the supports 24 and 25 as the members 21 and 22 spread and come together. Pivotaly mounted in the casting 95 15 and in a screw 29 inserted in the boss 19 is a spindle 30 carrying a pointer 31 and a lever 32 at right angles to said pointer fast thereon. Any movement of the members 21 and 22 is communicated through levers 26 100 and 27 by means of a connecting link 33 to the arm 32, thus actuating the pointer 31. As the arm 32 is relatively short the motion of the thermostatic device is multiplied so that the pointer 31 makes a substantial 105 sweep for only a few degrees change in temperature. It will be noted that the lower end of link 33 is pivoted to arm 32, while the upper end terminates in a reduced portion 34 which loosely passes through the leg 27 and is so engaged by it. This expedient 110 is used only for the facility in assembling

the device. Pointer 31 is returned to the position corresponding to the minimum temperature by a spring 35 coiled about a peg 36 fast in casting 15 and having one end 5 secured in said casting at 37 and the other end 38 engaging pointer 31 through a link 39. Adjustment of the position of pointer 31 may be made by rotating members 21 and 22 to screw the stud 20 in its boss 18, and 10 the same may be held in position after it has been set by a set-screw 73 screwed into the support 17 and engaging said stud.

Pointer 31 serves as a movable contact member which engages a number of fixed 15 contact members best shown in Fig. 1. The latter contact members comprise two end members 40 and 41, of which member 41 is the more extensive, and several intermediate members 42 and 43. Members 40 and 41 20 are provided with ears 44 and 45 which are clamped together by screws 46 and 47, thus holding all the contact members together and insulated from each other. The combined contact members thus formed are arranged 25 in the arc of a circle whose center is the pivot 14 and are supported from screw 46 by a single angular bracket 48 attached to the back 10. The whole can thus more easily be adjusted and aligned. Pointer 31, as best 30 shown in Fig. 2, is formed with a contact head 49 which engages the fixed contact members as the temperature changes and successively completes the various circuits through them. All of the contact members 35 and the part 49 of pointer 31 may be seen from without the device through a window 72 in the case 13.

It will now be comprehended that if the casting 15 is rotated upon the pivot 14 the 40 whole thermostatic device including the pointer will be rotated relatively to the fixed contact members. The means for oscillating and locking the same will now be described. Casting 15 is provided at its lower extremity 45 with a peg 50 slidable in a slot 51 in a lever 52, which lever is itself pivoted to the back 10 by a screw 53 passing through a slot 54 in said lever. Lever 52 extends out through the bottom of the case 13 and is bent forward 50 on itself and terminates in a pointed head 55 engageable in a notched segment 56 secured to the back 10 through ears 57. A diagonally-positioned spring 58 secured to the back 10 and the lever 52 tends to draw the 55 same to the right and upward into engagement with the segment 56. In order to set the device for different room temperatures the lever 52 is pulled downward by the head 55 and the casting 15 shifted.

60 It is often desirable to automatically shift the lever 52 to increase the room temperature to a predetermined degree. To this end I provide a U-shaped lever 59 having legs 60 and 61 pivoted to the back 10 at 62. The leg 65 61 is adapted to engage a catch or projec-

tion 63 issuing from a raised portion 64 of the lever 52, so that as the lever 59 is moved downward the lever 52 is also moved downward, and when the catch 63 is near the center of oscillation of lever 52 the same comes out beyond the head of screw 53 and the pointed head 55 is released from the segment 56 and lever 52 drawn to the right by the spring 58. The release of lever 52 when catch 63 is located near screw 53 prevents 70 sliding of the catch 63 upon the leg 61 and hence facilitates the movement of the lever 52. Lever 59 is given its downward motion by the alarm winding stem 65 of an ordinary alarm clock 66, removably attached to the 80 case 13 by a snap lever 73, as clearly indicated in the drawing. A lever 67, similar to lever 52, having a head 68 engageable in the segment 56 and a groove 69 through which the screw 53 passes, is used as a stop for 85 procuring the desired room temperature when the lever 52 is automatically released by the clock 66. Lever 67 can be set along segment 56 by hand and is held set by a spring 70 connecting it with the back 10. 90

The contact members, as well as the pointer, are connected to a series of binding posts 72 by leads 71 running along the inside of the back 10. The thermostat may be connected by means of the binding posts 72' 95 with any suitable form of operating device which may be employed to regulate the source of heat.

In some cases it will be found that it may be desirable to have the thermostatic members 21 and 22 in the open, and to this end I modify the casing 13 to appear as shown in Fig. 3. The thermostatic members 21 and 22 and all the actuating mechanism within the casing may be the same as that of the 105 form shown in Figs. 1 and 2. The case 75 in this form is made with a perfectly flat face having an aperture 76 in the same for allowing member 22 to protrude out through said case. Aperture 76 is formed at 77, as 110 seen in Fig. 5, to permit the support 15 to freely oscillate as before described, and member 21 fits loosely into the aperture 76 to substantially inclose the operating mechanism from the exterior. This form of casing 115 may have a guard 78 attached to its sides as shown in Figs. 4 and 5, which guard passes about the thermostatic members 21 and 22, protecting them from injury, and still allows currents of air to pass up and down through 120 its open ends 79 and 80 to actuate the device, and may also have a thermometer 81 attached to its exterior.

The advantages of my invention are manifest. Placing the thermostatic members in a plane parallel to the back reduces the space occupied by the device. The arrangement of the contact members permits of easy adjustment of the same. The number of parts and their construction render the de- 130

vice less expensively constructed and insures more positive action.

I claim:

1. A thermostat comprising a back, an arm formed near the center of said back and spaced therefrom, a thermostatic member secured to said arm, a pointer pivoted between said arm and said back, a support formed on the upper portion of said back extending outward beyond the plane of said thermostatic member, a bell crank pivoted to said support having one arm engaging the center of the outer surface of said thermostatic member and the other arm extending at right angles thereto along said support, and a link connecting said bell crank and said pointer and extending between the arm and thermostatic member and said back for operating the pointer.
2. A thermostat comprising a back, a supporting member pivotally secured to said back, a thermostatic member fixed on said supporting member, a pointer pivoted upon said supporting member and actuated by said thermostatic member, contact members fixed upon said back and engaged by said pointer, a lever slidably pivoted to said back, a notched segment, a head on said lever engaging said segment, and a spring for causing said head to engage said segment.
3. A thermostat comprising a back, a supporting member pivotally secured to said back, a thermostatic member fixed on said supporting member, a pointer pivoted upon said supporting member and actuated by said thermostatic member, contact members fixed upon said back and engaged by said pointer, a lever for oscillating said supporting member, means for automatically oscillating said lever, and an adjustable stop for limiting said oscillation.
4. A thermostat comprising a back, a supporting member pivotally secured to said back, a thermostatic member fixed on said supporting member, a pointer pivoted upon said supporting member and actuated by said thermostatic member, contact members fixed upon said back and engaged by said pointer, a lever slidably pivoted to said back, a notched segment, a head on said lever engaging said segment, a spring for causing said head to engage said segment and for oscillating said lever in one direction, means for automatically sliding said lever to disengage said head from said segment and release the lever, and an adjustably-positioned stop for limiting the oscillation of said lever.

5. A thermostat comprising a fixed member, a supporting member rotatably mounted thereon, a thermostatic member fixed on said supporting member, a projecting member attached to said supporting member, a bell-crank pivoted to said projecting member having one arm thereof engaging the thermostatic member and the other arm extending toward said supporting member, a pointer pivoted to said supporting member, a link connecting said last mentioned arm and said pointer, contact members on said fixed member engaged by said pointer, a lever movably mounted on said fixed member, a pivotal connection between said lever and said supporting member, means for holding said lever in a definite position, means tending to move said lever in one direction, and means for automatically releasing said lever to permit it to move into another position.

6. A thermostat comprising a fixed member, a supporting member rotatably mounted thereon, a thermostatic member fixed on said supporting member, a pair of lugs attached to said supporting member extending beyond said thermostatic member, a bell-crank pivoted to said lugs having one arm thereof engaging the thermostatic member and the other arm extending toward said supporting member, a pointer pivoted to said supporting member, a link connecting said last mentioned arm and said pointer, contact members on said fixed member engaged by said pointer, a lever slidably pivoted to said fixed member, a pivotal connection between one end of said lever and said supporting member, a notched segment secured to said fixed member, a head on the other end of said lever for engaging said segment, a spring for causing said head to engage the notches of said segment and for turning said lever in one direction, a U-shaped lever pivoted to said fixed member having one leg thereof engaging a projection on the slideable lever for sliding the same, means associated with the other leg of said U-shaped lever for automatically operating the same to release said slideable lever, and an adjustably-positioned stop for limiting the movement of said slideable lever.

In testimony whereof I affix my signature in presence of two witnesses.

EVERETT H. WHITE.
